UNITED STATES PATENT OFFICE

CHARLES A. UPSON, OF LOCKPORT, NEW YORK, ASSIGNOR TO THE UPSON COMPANY,
OF LOCKPORT, NEW YORK, A CORPORATION OF NEW YORK

INSULATING MATERIAL FOR BUILDING AND SIMILAR PURPOSES

Application filed August 29, 1929. Serial No. 389,301.

My present invention relates to building materials and more particularly to a prepared building material made ready to apply as an insulation for walls, ceilings, and floors, and it has for its object to provide an improved article of this nature which will lend itself in a peculiarly advantageous manner to the manipulations of the user in applying it, and at the same time provide an improved insulation medium particularly against the entrance or escape of heat and cold.

To these and other ends the invention resides in certain improvements and combinations of parts, all as will be hereinafter more fully described, the novel features being pointed out in the claims at the end of the specification.

In the drawing:

Fig. 1 is a fragmentary longitudinal central sectional view through a forming machine illustrating the manner in which my improved insulating material is produced;

Fig. 2 is an enlarged transverse sectional view through a strip of the material in its normal condition;

Fig. 3 is a view similar to Fig. 2 showing the strip bent transversely to conform to its intended position between the joists of a ceiling or floor or between the studding strips of a wall;

Fig. 4 is a further fragmentary sectional view showing the material of my invention bent and secured in place between the studding strips of a wall, and

Fig. 5 is a similar view showing two companion strips of the material similarly placed in a different manner between a plurality of adjacent studding strips.

Similar reference numerals throughout the several views indicate the same parts.

Referring first to Fig. 2 of the drawing there is there shown, as before stated, a transverse section of a strip of insulating material constructed in accordance with and illustrating one embodiment of my invention. It comprises a filler or interior body portion 1 of a flocculent fibrous material such as hair, cotton or an appropriate one of the substances usually employed in the making of carpet linings and building materials of this

general nature. I prefer to employ a mixture of short cotton fibers or cotton waste and jute, but this selection is immaterial to the objects of the present invention.

The interior body is faced and confined on both sides by liners 2 and 3 which have considerable tensile strength and may be composed, and preferably are composed of paper. The central portion of the strip is relatively thick and fluffy but the longitudinal edge portions indicated generally at 4 are relatively thin or compressed as clearly shown in Fig. 2. This thin edge may be produced by using less of the filler stock at these points or by compacting the stock or both. I prefer, in any event, to compact the filler stock at the edges by compressing and sewing the liners 2 and 3 together in this region as indicated at 5. I further prefer to first confine the said longitudinal edges 4 of the bat between paper or similar strips 6 arranged on opposite sides and through which the line of stitching 5 is made. The liners 2 and 3 are later pasted thereon with an adhesive that secures the stitches to the strips 6 and prevents the bat from later expanding at these edge portions. There is thus produced a permanent thin edge portion with a soft and expandable center portion.

This insulating bat or strip as described and as essentially shown in Fig. 2 may, with the changes hereinafter described, be produced on a machine of the nature of and in accordance with the general method set forth in my prior Patent No. 1,713,309, of May 14, 1929. I have shown the essential and modified element of this machine in Fig. 1, referring to which 1 indicates the bat alone suitably formed and traveling on tables 7 and 8 in the direction of the arrows between presser rolls 9. An apron conveyer traveling over the table and around the appropriate rolls 10, 11, and 12 is shown at 13. The strips 6 are fed on to the bat at its edges and under the guide rolls 14. They thence pass to the needles 15 of the sewing machine which form the stitching 5. Acting in conjunction with these needles (there being of course a plurality of the same) are presser feet 16 in the manner of an ordinary

sewing machine. The action of these presser feet, acting in the ordinary manner, presses the bat 1 and the reinforcing strips 6 to a sufficient degree to produce the desired relative thinness and compactness at the edges 5 of the bat, and the stitching extending through the strips 6 and the filling between them holds the filling in this relatively thin condition, resisting any tendency for it to 10 spring back to its original thickness. If necessary an additional compression device, acting ahead of the needles may be provided in the form of spring pressed rollers 17. After the reinforcing strips 6 have been applied and stitched to the filling, the liner 15 sheets 2 and 3 may be applied to the top and bottom of the bat in any suitable manner, such as by the same mechanism shown in said prior Patent No. 1,713,309 for applying the liner sheets 5 and 5a.

20 The utility of a thin edged insulating strip formed and constituted as described may be explained as follows:

In Fig. 4 A indicates adjacent studdings 25 of a wall in horizontal section and B indicates sheathing applied thereto. The lathing or other plaster support C is applied to the interior of the studding, the plaster being indicated at D. The function of the insulation of this invention is to occupy the 30 interior space. It is applied, under one system, in the manner shown in Fig. 4 in which nailing strips E secured the thin edges 4 to the opposite inner side of the studding pieces 35 A. The operation of bending the insulating strip to this position causes it to assume the curved position shown in which there are air spaces F between it and the sheathing and air spaces G on the opposite sides between it 40 and the interior finish or wall forming elements C and D. Thus two separate air spaces are provided instead of one which, as anyone skilled in the art will see, adds greatly to the insulating qualities from this 45 standpoint alone.

But in addition to this the flexing of the insulating strip to this position with its edges so compressed and confined contributes another insulating factor. This resides in 50 the expansion of the fibrous body 1 at the center, as shown in Figs. 3 and 4, which results from the fact of the bending of the material while the edges are held fast in their compressed condition. Were they not 55 so held fast the insulating strip would not accommodate itself to the position shown but would have a tendency to crinkle or break indiscriminately throughout its width and there would be a further tendency for it to 60 expand and pull away from the liners at the edges where it must be fastened instead of expanding as aforesaid at the center where such expansion adds to its insulating qualities.

65 In Fig. 5 the same action is shown where

the thin edges 4 of the insulating strips are secured to the inner surfaces of the studding pieces A beneath the lathing C instead of at the sides of the studs entirely within the wall cells. 70

I claim as my invention:

1. A padded product for the insulation of the walls of buildings and similar purposes which comprises in combination an inner flocculent mass of fibrous material confined between liner sheets having relatively greater tensile strength, the longitudinal edges of the product being compressed throughout a substantial width to a greater degree than intermediate portions thereof. 75 80

2. A padded product for the insulation of the walls of buildings and similar purposes which comprises in combination an inner flocculent mass of fibrous material confined between liner sheets having relatively greater tensile strength, the longitudinal edges of the product being compressed to a greater degree than intermediate portions thereof and being secured in such compressed state of lines of stitching extending through said fibrous material. 85 90

3. A padded product for the insulation of the walls of buildings and similar purposes which comprises in combination an inner flocculent mass of fibrous material confined between liner sheets having relatively greater tensile strength, the longitudinal edges of the product being compressed to a greater degree than intermediate portions thereof and being secured in such compressed state by 95 lines of stitching, the lines of stitching passing through reinforcing strips extending along said longitudinal edges. 100 105

4. A padded product for the insulation of the walls of buildings and similar purposes which comprises in combination an inner flocculent mass of fibrous material confined between liner sheets having relatively greater tensile strength, the longitudinal edges of the product being compressed to a greater degree than intermediate portions thereof and being secured in such compressed state by lines of stitching, the lines of stitching passing through reinforcing strips extending along 110 said longitudinal edges on the inner sides of the liner strips and next to the flocculent inner mass of fibrous material. 115 120

5. An insulating bat for application to walls of buildings and the like, said bat comprising a filling of loosely associated fibres and a liner of sheet material on each side of said filling, said filling having along each of two opposite edges a marginal portion of less thickness than the main portion of said filling, each of said marginal portions being of substantial width so that such portions may be bent at an angle to the main body of said bat for easy application to walls. 125 130

6. An insulating bat for application to walls of buildings and the like, said bat com-

prising a filling of loosely associated fibres and a liner of sheet material on each side of said filling, said filling having along each of two opposite edges a marginal portion of less thickness than the main portion of said filling, each of said marginal portions being of substantial width so that such portions may be bent at an angle to the main body of said bat for easy application to walls, and stitching extending through the filling of each marginal portion at an intermediate point thereof.

7. An insulating bat for application to walls of buildings and the like, said bat comprising a filling of loosely associated fibres and a liner of sheet material on each side of said filling, said filling having along each of two opposite edges a marginal portion of less thickness than the main portion of said filling, each of said marginal portions being of substantial width so that such portions may be bent at an angle to the main body of said bat for easy application to walls, a reinforcing strip on each side of each marginal portion, and stitching extending through the filling of each marginal portion and through the reinforcing strips associated therewith.
